UNITED STATES PATENT OFFICE.

JAMES L. KERSHAW, OF CLEVELAND, OHIO; W. M. BALDWIN, ADMINISTRATOR OF SAID JAMES L. KERSHAW, DECEASED, ASSIGNOR, BY DIRECT AND MESNE ASSIGNMENTS, OF ONE-FIFTH TO ADOLPHUS L. KERSHAW AND ONE-FIFTH TO ISABELLA KERSHAW, OF CLEVELAND, OHIO.

BENDING-MACHINE.

1,304,326.

Specification of Letters Patent.

Patented May 20, 1919.

Application filed April 23, 1915. Serial No. 23,512.

To all whom it may concern:

Be it known that I, JAMES L. KERSHAW, a citizen of the United States, and resident of Cleveland, in the county of Cuyahoga and

5 State of Ohio, have invented certain new and useful Improvements in Bending-Machines, of which I hereby declare the following to be a full, clear, and exact description, such as will enable others skilled in the art 10 to which it appertains to make and use the same.

The objects of the invention are to provide a machine for bending in a lateral direction flat bands of metal, and also metal shapes 15 which include in their construction flat bands or bars having laterally extending members, such as angle bars and channel bars.

The invention includes means for bending the band into a circular form, by exerting lateral pressure at spaced points thereon while securing the intermediate part from movement and exerting vertical pressure to retain the band in its flat condition, and in the case of bending metal shapes which include a horizontal flat member and vertical members or flanges integral with the horizontal member, the machine is designed to exert a sufficient vertical pressure to not only retain the device in its horizontal plane 25 while it is being laterally bent, but also sufficient to permanently overcome the inherent elasticity of all parts thereof and especially to apply on all parts sufficient pressure to retain them in shape after they are released 30 from the machine.

The invention comprises a heavy press in which horizontally and vertically moving formers are employed to compress and shape the metal.

40 It also includes means for efficiently and positively adjusting the amount of relative movement of the formers and for obtaining perfect control of the amount of bending desired in the article in any direction to correct any distortion therein, and to increase or diminish the pressure at any point therein.

The invention is further designed to act automatically upon cold metal and to bend 50 the metal without leaving evidence of swaging or bruising in any manner thereon, which will interfere with its appearance or sale, to produce a substantially correct degree of curvature, and also provide for the

retreatment of any one portion of the metal 55 arc.

The invention further includes means for operating the individual sets of formers alternately, thus reducing the amount of power required to operate the machine. 60

The invention further comprises the combination and arrangement of parts and construction of the various details hereinafter described, shown in the accompanying drawings and specifically pointed out in the 65 claims.

In the accompanying drawings Figure 1 is a perspective view of the device; Fig. 2 is a plan view of the device on central plane; Fig. 3 is a side elevation with gearing removed; Fig. 4 is an elevation of the front side thereof; Fig. 5 is a longitudinal vertical section on central plane; Fig. 6 is a plan view of the horizontal cross head, showing the attached formers; Fig. 7 is a perspective 70 view of the forward or central die or abutment against which an angle bar is bent when the horizontal flange or leg is inside the curve; Fig. 8 is a perspective view of sets of blocking wedges which fill the space between the forward portion of the bed and the forward dies; Fig. 9 is a sectional view on a central vertical plane showing the form 75 and arrangement of forming dies for bending angle bars with the horizontal flange or leg outside of the curve; Fig. 9^a illustrates an additional plate employed therewith; Fig. 10 is a similar view on a central vertical plane showing forming dies for bending 80 channel bars; Fig. 10^a illustrates a modification thereof; and is a vertical central section; Fig. 11 is a side elevation of a bar feeding device which is operated by hand; Fig. 12 is a plan view of clamps which hold the adjusting nut in each of the cross heads. 85

In these views A is the horizontal bed plate of the machine and B is a vertical portion thereof. C represents the bar to be operated upon, which moves transversely of the bed plate in the opening c arranged to 90 receive it.

In Figs. 1 and 5 the construction of forming dies and their mode of operation is shown. Here horizontally moving bending die blocks D, D, are spaced apart upon a 105 cross head D', D'', which reciprocates in suitable guides or gibbs D³ upon the bed plate A, and the cross head is operated by

means of an eccentric E and main shaft E', and the cross head is formed in two portions D', D² relatively adjustable to each other by means of a screw F, one end of which is secured in the main portion D' of the cross head and is operated by means of the nut F' which is rotatably mounted to engage the other portion and is attached thereto by means of straps f, f, which engage 10 grooves f', f', in the nut.

The nut is preferably operated by means of the spur gears F², F³, and rod F⁴ and bevel gears F⁵, F⁶, and operating wheel F⁷, positioned where it is readily accessible to 15 the operator.

This screw gives possibilities of fine adjustment to the cross head and bending dies.

The abutment against which the central portion of the bar is pressed includes preferably the blocking and adjusting wedges as 20 shown in Fig. 5, and which corresponds with the forms employed in bending an angle bar having the flange or leg inside.

Here G is a block which is suspended from 25 a vertically moving cross head H, and which substantially fills the angle of the bar, and rests upon the lower flange. G' is a second block engaging the block G and having a wedge g in its lower edge which is horizontally adjustable by means of screws g' to engage and press upon the outer edge of the angle bar.

In addition, further blocks I and I' fill 30 the space between the angle bar and a vertical thrust block J at the end of the machine.

The blocks I and I' may comprise also 35 vertical wedges adjustable by means of screws i, i, for use in bending bars, with the flange extending outwardly as will be described hereinafter. When the position of the cross head has been adjusted by means of the screw F the forward movement of the cross head will compress the vertical leg or flange of the angle bar against the filling 40 blocks G' and I and thrust block J and by means of the wedge g and the interposed thin bar g³ the horizontal leg or flange will also be tightly engaged, and held in place 45 while the spaced forming dies are bending 50 the bar.

The effect of bending the angular bar in this manner with the horizontal flange on the inside is to stretch the outer edge of the angle and to compress the inner edge of the 55 horizontal flange. The vertical flange will also bend horizontally to correspond to the curvature of the angle bar, but will not be able to retain its shape when removed from the press, without previous pressure applied 60 thereto in a vertical direction, since the horizontal pressure thereon will not stretch the upper edge of the vertical flange as much as the lower edge is stretched at the angle. That is the upper edge will bend without 65 stretching the result being that when re-

leased the bar will curve upward unless vertical pressure is first brought to bear upon the bar upon each side of the central bearing K to stretch the upper edge until it is the same length as the lower edge and the 70 natural elasticity thereof has been overcome.

The bar is therefore strained downward on each side of the central bearing k by means of pressure dies H², H² one arranged at each side of a vertical cross head H and 75 engaging the upper edge of the vertical flange of the angle bar on each side of the center of the machine, and equally spaced from the central bearing k which is slightly raised above the bed plate.

The lower edge of the cross head is also centrally cut away at h to permit of the vertical straining of the angle bar.

The central thrust block G shows a slight projection at its lower front edge which 80 engages the front edge of the horizontal flange and prevents it from buckling when compressed. This block is connected centrally with the vertically moving cross head by means of the forked clamp or chain L 85 which engages with projections l, l, upon the block, and is made adjustable by means of wedging blocks m and n, the parts being secured detachably to the cross head by means of bolts o, o, in separable parts H, H'. 90

This cross head is made vertically adjustable by means of the screw P attached to one portion H and the nut Q attached to the other portion H' and rotatable therein. The downward pressure is obtained by means of 100 the wedge R horizontally movable in the vertical portion B of the bed plate, and is returned by means of the springs S, S, which operate upon rods S', S', secured in the upper portion of the cross head.

The plates T, T, upon the upper portions of the cross head enter the groove t in the nut and lift the lower portion of the cross head. By tightening the bolts t, t' sufficient friction can be brought to bear upon the nut 110 to prevent it from turning under the jarring action of operating.

The wedge is operated by means of a cam W upon a shaft W' and this cam is designed to give a constant pressure commencing in 115 advance of the movement of the horizontal crosshead, and holding the pressure rigidly until the horizontal formers cease to work when the wedge is immediately withdrawn and the spring raises the vertical crosshead. 120 The bar is then released by both crossheads and can be moved forward for repetition of this treatment.

A device is shown for moving the bar forward periodically for a short distance when 125 the described treatment is repeated, until the entire length of the bar is bent.

This is accomplished by means of a lever Z pivoted at Z' to the machine, and provided with a chisel shaped gripping pawl or dog 130

⁵ Z^2 which will act to feed the bar forward when the lever is moved forward, but will slip when the lever is moved backward. The chisel is so shaped as to accomplish this result.

Stops Z^3 , Z^4 are adjustably secured to the frame of the machine to determine the amount of feed of the bar at each movement of the forming dies.

- ¹⁰ 10 A clutch V , V' , shown in Fig. 2 permits of disconnecting the cam shaft temporarily from the hub V' of the operating gear V^2 so that the position of the vertical cross head and dies thereon can be independently ⁷⁰ adjusted, and by disconnecting these parts the lower portion of the machine can be used independently of the upper portion.

The machine is operated by means of a band fly wheel V^3 driving shaft V^4 , pinion ²⁰ V^5 and gears V^6 and V^7 on the shaft E' which operatively connect the parts together.

In case the angle shows a tendency to bend down the additional horizontal wedges U , U can be employed adjustably secured at the ²⁵ extreme edges of the bed plate, to overcome this tendency. By use of these wedges if they are inserted far enough beneath the angle bar the bar can be bent into a spiral if desired.

- ³⁰ 30 In Figs. 9 and 9^a are shown the construction of the forming dies employed in bending an angle bar with the leg or flange on the outside of the curve.

Here the bending dies D , D' , and cross ³⁵ head D' remain the same with the exception that an extension d is added to each one which practically fits the angle and is shown in dotted lines in Fig. 9.

The bearings K' , K^2 , are also moved to a ⁴⁰ position underneath the vertical flange and are spaced apart the pressure from above being applied in the center of the space between them. The pressure from above is applied by means of the central block d' attached to the vertical cross head H .

The abutment J and filling blocks I and G' are employed but an additional central block I^2 upon which the bar is bent is required. No plate similar to plate g^3 Fig. ⁵⁰ 5 is required.

By means of this construction the tendency of an angle bar to curve downward at the ends when bent in this manner is overcome, and since this tendency will be the ⁵⁵ reverse from that of a bar bent as previously described, a slight change in the forms of bearings and dies is required.

The action of the horizontal pressure is to expand the outer edge of the horizontal ⁶⁰ flange and to contract the inner edge at the angle and an equal amount of contraction is not produced at the upper edge of the vertical flange unless vertical pressure is applied thereto between two bed plate bearings K' until an equal amount of contrac-

tion of both edges of the vertical flange is obtained.

In Figs. 10 and 10^a are shown modified forms of dies employed in bending a channel bar edgewise. ⁷⁰

Here X is a vertical die formed in two portions which is so formed to make it release itself when the cross head and part of the die rises and also it is adjustable as shown in Fig. 10 to different sizes of channel ⁷⁵ bars and is designed to substantially fill the inclosed space between the vertical flanges, one portion is attached to the cross head and the other remains in the channel. The rest plate or bearing K' is in the center and ⁸⁰ the plates K^2 are spaced from the center. The filling blocks are the same as in Fig. 9. In Fig. 10^a a filling piece X' is inserted between.

The action upon the channel bar combines ⁸⁵ the results obtained in both Figs. 5 and 9 viz. of putting the bar under vertical pressure beyond the limit of elasticity to expand the upper edge of one flange and to contract the upper edge of the other flange while the ⁹⁰ horizontal dies are shaping the bar.

Having described the invention what I claim as new and desire to secure by Letters Patent is:

1. In a machine for bending a metal bar ⁹⁵ having horizontal and vertical flanges, a bed plate upon which said bar rests, vertically acting holding and straining devices for said bar adapted to retain said bar in position and to overcome the tendency there- ¹⁰⁰ of to become distorted when horizontally bent, and subsequently and horizontally acting bending devices including a stationary central abutment engaging one edge of said horizontal flange and spaced horizontally ¹⁰⁵ moving members engaging the other side of said horizontal flange and engaging one face of said vertical flange.

2. Means for bending a metal bar having horizontal and vertical flanges, in the plane ¹¹⁰ of the horizontal flange, including devices for first straining said vertical flange in the direction of its plane beyond the elastic limit thereof, to prevent subsequent distortion thereof, and subsequently acting means ¹¹⁵ for bending the horizontal plane into the predetermined arc comprising a fixed abutment, engaging one edge of said horizontal flange, and spaced horizontally moving members engaging the other edge of said horizontal flange, and a vertical face of the vertical flange. ¹²⁰

3. Means for bending a metal bar having horizontal and vertical flanges, in the plane ¹²⁵ of the horizontal flange, including devices for first straining said vertical flange in the direction of its plane beyond the elastic limit thereof, to prevent subsequent distortion thereof, and subsequently acting means for bending the horizontal plane into the prede- ¹³⁰

terminated arc comprising a fixed abutment, engaging one edge of said horizontal flange, and spaced horizontally moving members engaging the other edge of said horizontal flange, and a vertical face of the vertical flange, and means for alternately operating said vertically and horizontally moving mechanism.

4. In combination, in a machine for bending metal bars having horizontal and vertical flanges in the plane of one flange, a frame and a bed plate upon which the bar rests, a vertically reciprocating cross head in said frame, means upon said cross head for engaging the free edge of one flange to strain the same to a predetermined degree, and also engaging means on said cross head for the flat surface of the other flange, an operating means for said cross head having a short period of action and a long period of rest, and a period of quick return, and subsequently acting means for bending the bar in the direction parallel to the plane of the other flange, including an abutment upon

said base, a reciprocating cross head opposed thereto and provided with spaced engaging parts, and means for adjusting the operating means for both said cross heads.

5. In a bending machine, in combination, a frame, a vertically reciprocable and longitudinally adjustable cross head in said frame, an operating wedge in said frame engaging said cross head, an actuating cam for said wedge, and a subsequently acting horizontally reciprocable and horizontally adjustable cross head in said frame, and an actuating cam therefor, cam shafts for the respective cams, operating means for said shafts, and an adjustable abutment in said frame opposed to said horizontally reciprocating cross head.

In testimony whereof I hereunto set my hand this 16th day of April, 1915.

JAMES L. KERSHAW.

In presence of—

RALPH W. JEREMIAH,
W.M. MONROE.
